ATTORNEY

UNITED STATES PATENT OFFICE

133,869

DESIGN FOR A TOY RATTLER

James P. Donahue, Oak Park, Ill.

Application July 13, 1942, Serial No. 107,518

Term of patent 14 years

To all whom it may concern:

Be it known that I, James P. Donahue, a citizen of the United States and a resident of Oak Park, county of Cook, and State of Illinois, have invented a new, original, and ornamental Design for a Toy Rattler, of which the following is a specification, reference being had to the accompanying drawing, forming part thereof.

In the drawing:

Figure 1 is a perspective view of a toy rattler showing my new design.

Figure 2 is a side view in elevation of the toy rattler shown in Figure 1, with the intermediate movable rollers equally spaced relative to the fixed end rollers.

Figure 3 is a side view in elevation corresponding with Figure 2, except that the intermediate movable rollers are displaced for contact with the fixed end rattler roller.

Figure 4 is a front view in elevation of the toy rattler shown in the preceding figures.

The toy rattler embodying my new design involves rattler rollers axially movable on a rod having fixed end pieces serving to limit the movable rollers.

I claim:

The ornamental design for a toy rattler, substantially as shown and described.

JAMES P. DONAHUE.
